UNITED STATES PATENT OFFICE.

ARMANDO ZANOTTA, OF MILAN, ITALY.

ELECTRIC-ARC LAMP.

1,130,460.

Specification of Letters Patent.

Patented Mar. 2, 1915.

Application filed October 31, 1914. Serial No. 869,657.

To all whom it may concern:

Be it known that I, ARMANDO ZANOTTA, a subject of the King of Italy, residing at Via Borgogna No. 8, Milan, in the Kingdom of Italy, have invented certain new and useful improvements in Electric-Arc Lamps; and I do hereby declare the following to be a full, clear, and exact description of the invention, such as will enable others skilled in the art 10 to which it appertains to make and use the same.

This invention relates to improvements in electric arc lamps.

At present the lamps for cinematographic 15 projections consist of a voltaic arc and the excess of tension, which normally exists—the tension of line generally having a value corresponding to about the triple of that necessary for the working of the arc—is absorbed through resistances and produces a 20 useless wasting of energy, and, what is worse, a development of heat, which is the more harmful and dangerous being in the vicinity of substances very easily inflammable, as the cinematographic films.

One object of my invention is to produce a projecting lamp which shall comprise means to provide a plurality of arcs disposed in series, so that they will absorb 25 themselves, without need of additional resistance, most of the tension on the line, and in this way, by smaller consumption of current, effect a greater luminous intensity, because a larger amount of the energy, instead 30 of being uselessly absorbed by resistances, is transformed into light.

A further object is to provide simple and efficient means whereby the electrodes of the lamp may be quickly and accurately adjusted 40 with relation to each other and to the lens of the apparatus.

With these and other objects in view, the invention consists in certain novel features of construction and combination of parts as 45 hereinafter set forth and pointed out in the claims.

The accompanying drawing is a view, partly in section and partly in elevation, showing an embodiment of my invention.

50 In the lamp shown in the drawing, carbons 33 and 34 are supported, respectively, by holders 35 and 36 carried by arms 37 and 38; the latter being carried by bars 39 and 40. The bars 39, 40, are guided in a 55 support 41 and can be made to run longitudinally in reverse direction, so as to ob-

tain the recession or the approach of the arms 37 and 38 and, therefore, also of the carbons 33 and 34. This opposite movement of the bars 39 and 40 is produced by a pinion 60 42 gearing with racks 43 and 44 on the bars 39 and 40, and disposed in such a manner to be placed one at one side, and the other at the other side, of the pinion 42. This pinion carries a screw prolongation 45 65 which enters a threaded socket in an intermediate bar 46, the latter being guided in the support 41, and, to this intermediate bar, an intermediate holder 47, for a carbon 48, is hinged. By working the pinion 70 42, by the aid of rod 49, the lowering or the elevations of the carbons 33 and 34 and the advancement or the retrocession of the carbon 48, are contemporaneously caused; that is to say, the approach or the recession of the 75 three carbons, one in respect to the others, may be effected.

The upper arm 38 is hollow and has such a form that the piece 51, which constitutes part of the carbon holder, 35, may be caused 80 to run forward and backward by the rotation of a threaded rod 50 swiveled in the arm 38 and entering a threaded socket in said piece 51. By operating the rod 50 the carbon 33 may be caused to advance or to 85 recede. Moreover, the arm 38 is joined to the bar 40 so that it may turn with respect to the axis of the latter. Such a rotary movement may be transmitted to the arm 38 by means of a rod 52 and bevel gearing 53 and 90 54. A rod 55, mounted in an arm 55^a, carries a worm 56 meshing with said metal worm 57 made rigid with the holder 47 which carries the carbon 48. By operating the rod 55 the carbon 48 may be angularly 95 displaced so as to approach more or less to one or the other of the carbons 33 and 34. Now by working the bars 50, 52 and 55, the positions of the carbons 33 and 48, in respect to the other carbon 34, may be 100 respectively regulated. The regulation of the three carbons in respect to each other, is obtained by operating the rod 49.

The lamp may be adjusted laterally by a gear 60 engaging a rack 61 in the lamp 105 frame, said gear being carried by a manually operable shaft 59. Backward and forward adjustment of the lamp may be effected by screws 65, and the lamp may be adjusted vertically by means of rack and 110 pinion gearing 63—64 controlled by a manually operable shaft 62. The lamp and its

electrodes will, in all cases be adjustable with respect to the lens of the projecting apparatus, said lens being shown diagrammatically in the drawings at 66.

5 Having now particularly described and ascertained the nature of the said invention, and in what manner the same is to be performed, I declare that what I claim is:

1. In a projection apparatus, a lens, 10 means for holding three electrodes so as to converge toward the lens with one of the electrodes in substantial alinement with the axis of the lens, and means for moving said latter electrode axially and the other two 15 electrodes toward and away from it.

2. In a projector type arc lamp, a lens, means for holding three electrodes in substantially the same plane, with the outer two inclined with respect to the central electrode 20 to cause the three to converge toward a common point with the axis of the central electrode substantially coincident with the axis of the lens, means for moving the outer two electrodes toward and from the axis of the 25 third or central electrode and for moving the latter axially, respectively, toward and away from the point of convergence of the electrodes.

3. In a projector type arc lamp, means for 30 holding three electrodes in substantially the same plane, with the outer two inclined with respect to the central electrode to cause the three to converge toward a common point, manually operable means for simultaneously 35 moving the outer two electrodes toward and away from the axis of the third or central electrode and for moving the latter axially, respectively, toward and away from the point of convergence of the electrodes.

40 4. In a projection apparatus, a lens, means for holding three electrodes so as to converge toward the lens with one of the electrodes in substantial alinement with the axis of the lens, means for moving said latter electrode axially and the other two electrodes toward and away from it, including a support extending substantially parallel to the axis of 45 the central electrode, a holder for one of said electrodes slideable on said support and manually operable means for moving said holder relative to said support.

5. In a projection apparatus, a lens, means for holding three electrodes so as to converge toward the lens with one of the electrodes in substantial alinement with the axis of the lens, means for moving said latter electrode axially and the other two electrodes toward and away from it, and means for moving the end of one of the outer 55 electrodes toward or away from the plane defined by the axes of the other two electrodes.

6. In a projection apparatus, a lens, means

for holding three electrodes so as to converge toward the lens with one of the electrodes in substantial alinement with the axis 65 of the lens, means for moving said latter electrode axially and the other two electrodes toward and away from it, including a support, overlapping bars, each provided with a rack, sliding in said support, electrode holders on said bars and a manually operable pinion coacting with said racks.

7. In a projection apparatus, a lens, means for holding three electrodes so as to converge toward the lens with one of the electrodes in substantial alinement with the axis 75 of the lens, means for moving said latter electrode axially and the other two electrodes toward and away from it, including a support, a holder for the central electrode 80 slideable in said support and a manually operable screw for moving said holder relative to said support.

8. In a projection apparatus, a lens, means for holding three electrodes so as to converge toward the lens with one of the electrodes in substantial alinement with the axis of the lens, means for moving said latter electrode axially and the other two electrodes toward and away from it, and means 85 for moving the end of the central electrode toward the end of one of the other electrodes and away from the end of the third electrode.

9. An arc lamp for cinematographic projections, comprising supporting means, three electrode carriers, one being intermediate of the other two, electrodes mounted in said carriers, the outer electrodes converging toward the central electrode whereby two separate arcs in series may be formed simultaneously, adjusting devices for the intermediate carrier, whereby the intermediate electrode may be moved laterally relatively to the other two, and means for laterally 95 adjusting one of said other two electrodes.

10. An arc lamp for cinematographic projections, comprising supporting means, a central electrode carrier, two lateral electrode carriers, electrodes mounted in said carriers, the outer electrodes converging toward the central electrode whereby two separate arcs may be formed in series, means for adjusting the two lateral electrode carriers toward or away from the central electrode carrier, and means for laterally 110 adjusting the central carrier.

In testimony whereof, I affix my signature, in presence of two witnesses.

ARMANDO ZANOTTA.
